UNITED STATES PATENT OFFICE

134,264

DESIGN FOR A DOOR CHIME OR SIMILAR ARTICLE

Gilbert P. Eagan, Deep River, Conn., assignor of one-third to Mary A. Eagan and one-third to Simon R. La Place, both of Deep River, Conn.

Application July 6, 1942, Serial No. 107,437

Term of patent 14 years

To all whom it may concern:

Be it known that I, Gilbert P. Eagan, a citizen of the United States, residing at Deep River, Saybrook, in the county of Middlesex and State of Connecticut, have invented a new, original, and ornamental Design for a Door Chime or Similar Article, of which the following is a specification, reference being had to the accompanying drawing, forming part thereof.

Fig. 1 is a plan view of the door chime showing my new design;

Fig. 2 is a side elevational view of the chime shown in Fig. 1; and

Fig. 3 is an end elevational view thereof.

I claim:

The ornamental design for a door chime or similar article, as shown.

GILBERT P. EAGAN.
